US00D755279S

(12) **United States Design Patent**
Valenti

(10) **Patent No.:** **US D755,279 S**
(45) **Date of Patent:** **** May 3, 2016**

(54) **SPORTS TRAINING GOGGLES**

(71) Applicant: **Swivel Vision LLC**, Orange, CA (US)
(72) Inventor: **Joseph James Valenti**, Orange, CA (US)
(73) Assignee: **Swivel Vision Sports LLC**, Orange, CA (US)

(**) Term: **14 Years**

(21) Appl. No.: **29/504,836**

(22) Filed: **Oct. 9, 2014**

(51) **LOC (10) Cl.** **16-06**
(52) **U.S. Cl.**

USPC **D16/312**

(58) **Field of Classification Search**

USPC ..... D16/101, 300-342, 900; D29/109, 110; D21/483, 659-661; 2/13, 15, 426-432, 2/447-449, 441, 434-437, 425, 439, 440, 2/443, 452; 351/41, 44-46, 51, 52, 59, 351/62, 63, 92, 103-123, 140-153, 158, 351/159, 162, 163, 83, 86; 434/36; 359/894 CPC A61F 9/00; A61F 9/02; A61F 9/022; A61F 9/023-9/029; A61F 9/045; A61F 2009/021; A61F 2210/009; G02B 27/0006; G02B 27/0075; G02B 27/0068; G02B 27/0062; G02B 27/0056; G02B 27/00; G02C 9/04; G02C 9/00; G02C 7/16; G02C 7/105; G02C 7/104; G02C 7/081; G02C 7/08; G02C 7/10; G02C 11/12

(57) **CLAIM**

The ornamental design for sports training goggles, as shown and described.

DESCRIPTION

FIG. 1 is a front, top, and left side perspective view of sports training goggles embodying my new design;
FIG. 2 is a rear, right, and top side perspective view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a top plan view thereof;
FIG. 8 is a bottom plan view thereof;
FIG. 9 is a front, top, and left side perspective view of a second embodiment of the sports training goggles;
FIG. 10 is a rear, top, and right side perspective view thereof;
FIG. 11 is a front elevational view thereof;
FIG. 12 is a rear elevational view thereof;
FIG. 13 is a right side elevational view thereof;
FIG. 14 is a left side elevational view thereof;
FIG. 15 is a top plan view thereof; and,
FIG. 16 is a bottom plan view thereof.
Broken lines and unshaded portions contained within broken lines are not claimed.
